BIRD FEEDING STATION

Helen Keith Sadler, Highland Park, Ill.

Application May 18, 1954, Serial No. 30,540

Term of patent 14 years

(Cl. D31—2)

Fig. 2.

Fig. 1.

Fig. 3.

To all whom it may concern:

Be it known that I, Helen Keith Sadler, a citizen of the United States, residing at 1855 County Line Road, Highland Park, in the county of Lake and State of Illinois, have invented a new, original, and ornamental Design for Bird Feeding Station, of which the following is a specification, reference being had to the accompanying drawings forming part thereof.

Fig. 1 is a side elevation of a bird feeding station showing my new design, a portion of the feeding plate being broken away to show the appearance of the structure behind the plate edge;

Fig. 2 is a top plan view; and

Fig. 3 is a sectional view taken on the line 3—3 of

I claim:

The ornamental design for a bird feeding station, substantially as shown and described.
